HEN'S NEST

William W. McCoy, Chehalis, Wash.

Application November 9, 1937, Serial No. 173,672

1 Claim. (Cl. 119—50)

The invention relates to a hen's nest and more especially to an automatic opening and closing nest.

The primary object of the invention is the provision of a nest of this character, wherein the construction thereof avoids the use of the nest by more than one hen at a time and in this connection avoids cannibalism among the hens during egg laying.

10 Another object of the invention is the provision of a nest of this character, wherein a hen on entering the nest causes the automatic closing thereof to the exclusion of other hens and when the hen leaves the nest it can make exit either 15 direction, there being openings at the front and rear of said nest, and the entering door at the front opening is automatically operated in the opening and closing thereof while the opening at the rear of said nest allows a person to remove a 20 hen from the nest when this may be required.

A further object of the invention is the provision of a nest of this character, which is simple in its construction, thoroughly reliable and efficient in operation, automatically acting, strong, durable 25 and inexpensive to manufacture.

With these and other objects in view, the invention consists in the features of construction, combination and arrangement of parts as will be hereinafter more fully described, illustrated in the accompanying drawing, which discloses the preferred embodiment of the invention, and pointed out in the claim hereunto appended.

In the accompanying drawing:

Figure 1 is a vertical longitudinal sectional view through the nest showing by full lines one position and by dotted lines another position in the working of said nest.

Figure 2 is a sectional view on the line 2—2 of Figure 1 looking in the direction of the arrows.

Similar reference characters indicate corresponding parts throughout the several views in the drawing.

Referring to the drawing in detail, the hen's nest constituting the present invention comprises an enclosure body 10 having opposed solid side walls 11 and opposite open ends 12 and 13, respectively. Within the body 10 is a tilting substantially hopper shaped nest proper 14 built upon a rocking plank 15 and adapted for occupancy by a hen for egg laying or hatching purposes.

This plank 15 is formed with a transverse axle 16 provided with trunnion ends 17 engaging bearings 18 fixed to and rising from block-like members 19 permanently set in the body 10 and in this

manner the nest proper 14 is swingingly supported.

Located at the open end 12 of the body 10 is a vertically swinging door 20 having fixed thereto at its bottom pintle eyes 21 accommodating a pintle 5 22 secured transversely at the lower portion of the open end 12 and fitted in the sides 11 of the body 10 so that in this manner the door 20 is susceptible of vertical swing for opening and closing movements with respect to the open end 12 of said 10 body 10.

Upon the outer face of the door 20 at its center and secured thereto in any suitable manner is a rib member 23 in which is fitted a transverse pivot 24 having connected thereto on opposite sides of the rib 23 a pair of links 25, these being also connected with a pivot 26 mounted transversely in a reduced front end 27 of the plank 15 so that when the nest proper 14 is occupied by a hen the door 20 automatically swings to closing position with 20 relation to the open end 12 of the body 10.

The plank 15 forwardly of the nest proper 14 carries thereon a counterweight 28 which is effective when the nest proper 14 is unoccupied to rock the plank 15 in a forward direction and thus 25 the door 20 becomes automatically open so that a hen can make exit from the body 10 through the open end 12.

Built on the side walls 11 interiorly of the body 10 are suitable ledges 29, these being elevated and 30 have removably supported thereby a shelf or platform 30, the latter being provided with the openings 31 accommodating pins 32 fixed in and rising from the ledges 29 for retaining the shelf or platform against displacement and removably held 35 on the ledges 29. When the hen enters or leaves the nest proper 14, it can lie or stand on the shelf or platform 30 in making an exit or entry from and to the body 10. The removal of the shelf on platform 30 allows access to the counterweight 28 40 carried by the plank 15.

Arranged at the open end 13 of the body 10 is a suspended door 33, being hung at 34 and this door through gravity makes contact with a stop 35 fixed in the open end 13 and precludes entry 45 through this open end 13 but allows exit therethrough from within the nest proper 14.

At the open end 13 is a shelf or rest 36 being carried inwardly and a hen within the body 10 can tread on this rest 36 when making exit from the 50 body 10 through the open end 13, the latter being for the particular purpose of allowing a person to remove the hen from the nest when this is required. When the door 33 is swung outwardly due to an exit from within by a hen through the 55

open end 13, it automatically gravitates to closing position in the open end 13, and by the presence of the stop 35 therein, a hen from without cannot gain access through the open end 13 to the interior of the body 10.

5 The construction of the nest assures against cannibalism and also avoids the crowding of the nest proper 14 or the breaking of the eggs held therein resultant from the entry of more than a single hen into the said nest. This nest proper 14 when occupied by a single hen traps the hen therein and when the said hen leaves the nest, it is free to make exit from the body 10 in the manner as before stated.

10 15 Should it be desired to trap a hen in the nest, the doors exteriorly thereof are manually latched in closed position in any suitable manner. A plurality of nest units constructed as before described are adaptable for stacking one upon the other within an enclosure.

20 What is claimed is:

25 A nest of the character described comprising a body forming an enclosure open at opposite ends, doors swingingly supported for closing said open ends, one of the doors being swingable vertically at the lower portion of one open end and the other door swingable vertically at the upper portion of

the other open end of said enclosure, a tilting plank arranged within the body, a frame forming the wall of a nest, said wall rising from said plank at one side of the tilting axis thereof and constituting with the plank a nest, trunnions fitted with the plank and constituting the tilting axis thereof, bearings within the body at the lowermost portion thereof and accommodating said trunnions, a counterweight on said plank removed from the frame and at the other side of the tilting axis of said plank, links pivoted to the plank and to the lowermost swung door for the closing of the latter when a hen occupies the nest, the counterweight being effective for the opening of the last-mentioned door when the nest is unoccupied, ledges fixed interiorly of said body, elevated above the weight and arranged between the nest and the last-mentioned door, a shelf fitting said ledges to be disposed for horizontal alignment and in the same plane with the last-mentioned door when in open position and having openings, and pins fixed in the ledges and received in the openings in the shelf for removal of the latter from said ledges and giving access to the counterweight.
